US00D654489S

(12) **United States Design Patent**
Weller et al.(10) **Patent No.:** **US D654,489 S**
(45) **Date of Patent:** **** Feb. 21, 2012**

- (54) **CASE FOR ELECTRONIC DEVICE**
- (75) Inventors: **Lucas Weller**, Fort Collins, CO (US);
Patrick Nelson, Loveland, CO (US)
- (73) Assignee: **Otter Products, LLC**, Fort Collins, CO (US)
- (**) Term: **14 Years**
- (21) Appl. No.: **29/400,059**
- (22) Filed: **Aug. 23, 2011**

Related U.S. Application Data

- (63) Continuation of application No. 29/398,226, filed on Jul. 28, 2011.
- (51) **LOC (9) CL.** **14-03**
- (52) **U.S. CL.** **D14/250**
- (58) **Field of Classification Search** D14/250–253, D14/440, 203.3–203.7, 217, 496, 248, 238.1, D14/140, 142, 143, 299; D3/201, 218, 269, D3/301, 273, 303; D13/103, 107–108; 220/4.02; 248/309.1; 361/679.56; 379/426, 433.11, 379/455; 455/575.1, 575.8; 190/100; 206/305, 206/320; 396/29, 448; 359/511; 348/373
- See application file for complete search history.
